C. Brown & Co.

UNITED STATES PATENT OFFICE.

JOHN T. NALLEY, OF MORGAN, TEXAS, ASSIGNOR OF ONE-HALF TO U. L. LOGAN, OF SAME PLACE.

SNAP-HOOK.

SPECIFICATION forming part of Letters Patent No. 552,695, dated January 7, 1896.

Application filed September 9, 1895. Serial No. 561,968. (No model.)

To all whom it may concern:

Be it known that I, JOHN T. NALLEY, a citizen of the United States, residing at Morgan, in the county of Bosque and State of Texas, 5 have invented a new and useful Snap-Hook, of which the following is a specification.

The invention relates to improvements in snap-hooks.

The object of the present invention is to 10 provide a snap-hook which will be adapted for use in connection with the various parts of harness and which will dispense with a spring for holding the parts together and which cannot in use accidentally open.

15 The invention consists in the construction and novel combination and arrangement of parts hereinafter fully described, illustrated in the accompanying drawings, and pointed out in the claims hereto appended.

20 In the drawings, Figure 1 is a perspective view of a snap-hook constructed in accordance with this invention. Fig. 2 is a side elevation of the same, the snap-hook being open. Fig. 3 is a side elevation of the opposite side 25 of the snap-hook, the parts being closed. Figs. 4 and 5 are detail perspective views of the parts separated.

Like numerals of reference indicate corresponding parts in all the figures of the drawings.

30 1 designates a snap-hook designed to be employed in connection with various parts of a harness or the like and comprising a main section or member 2 and a pivoted section or member 3. The main section or member 2 is provided with an integral loop 4, and it has a substantially elliptical opening 5, and is provided at one end of the opening with an entrance-slot 6, and the pivoted section or 35 member 3 is provided with a corresponding opening 7 and has an entrance-slot 8 at the opposite side thereof, whereby when the two sections have their openings substantially registering, as illustrated in Fig. 1 of the accompanying drawings, the entrance-slots will 40 be closed by the continuous sides.

The pivot 9, which connects the two sections or members, is located at about the center of the side of the main section having the 45 entrance-slot, and when the pivoted section is swung outward a notch 10, which receives

a ring 11^a, is adapted to carry the ring through the entrance-slot of the main section or member. The notch 10 is located at the upper side of the entrance-slot 8 of the pivoted section or member 3, and is partially closed by the continuous side of the main section when the snap-hook is closed, and prevents the ring from accidentally entering it. If the ring should bear against the pivoted member at the end of the opening adjacent to the entrance-slot of the main section or member, the pressure would fail to open the snap-hook, as the strain would be longitudinal instead of transverse.

55 The pivoted section or member is provided at its continuous side with a lug 11, which when the snap-hook is closed fits within and fills the entrance-slot of the main section or member, and this lug is adapted to support 60 and strengthen the parts and relieves the pivot of strain. The main section or member is provided at the inner end of the loop 4 with a boss or enlargement 12, and the pivoted section or member is provided with a 65 notch or recess to receive this enlargement or boss.

70 It will be seen that the snap-hook is exceedingly simple and inexpensive in construction, that it is adapted to be readily applied 75 to various parts of harness, and that it obviates the necessity of employing a spring for holding the parts together.

Changes in the form, proportion, and the minor details of construction may be resorted 80 to without departing from the principle or sacrificing any of the advantages of this invention.

85 What I claim is—

1. A snap hook, comprising a main section 90 having a ring receiving opening and having an entrance slot at one side at one end of the opening, a pivoted section provided with a similar opening and having an entrance slot at the other side and provided at the entrance 95 slot with a ring receiving notch arranged, when the pivoted section is swung outward to carry a ring through the entrance slot of the main section, substantially as described.

2. A snap hook, comprising a main section 100 provided with a loop and having a ring receiving opening and provided at one side with

an entrance slot, a pivoted section mounted on the main section and having an opening and pivoted at the opposite side with an entrance slot and having adjacent to such slot, 5 a ring receiving recess arranged to carry a ring through the entrance slot of the main section when the pivoted section is swung outward, and a lug arranged at the continuous side of the pivoted section and located 10 within the slot of the main section and filling

the same when the snap hook is closed, substantially as described.

In testimony that I claim the foregoing as my own I have hereto affixed my signature in the presence of two witnesses.

JOHN T. NALLEY.
